UNITED STATES PATENT OFFICE.

JAMES E. WRIGHT, OF BAY CITY, MICHIGAN.

AUTOMATIC RAILWAY-SWITCH.

950,254.

Specification of Letters Patent. Patented Feb. 22, 1910.

Application filed May 18, 1909. Serial No. 496,730.

To all whom it may concern:

Be it known that I, JAMES E. WRIGHT, a citizen of the United States, residing at Bay City, in the county of Bay and State of Michigan, have invented certain new and useful Improvements in Automatic Railway-Switches; and I do hereby declare the following to be a full, clear, and exact description of the invention, such as will enable others skilled in the art to which it appertains to make and use the same.

My invention relates to railway switches, one object being the provision of a switch which is capable of being closed automatically by a train running in either direction on the main line.

Another object is the provision of a switch which can be automatically opened by a train on the side track when about to pass onto the main line.

To these and other ends, my invention consists in certain novel features and combinations such as will be more fully described hereinafter and particularly pointed out in the claims.

In the accompanying drawings, Figure 1 is a plan view of the switch mechanism, Fig. 2 is a side view of the tripping mechanism carried by the train, Fig. 3 is a detail of the switch point operating means, Fig. 4 is a detail of one form of track instrument intended to be actuated by the tripping mechanism on the train, Fig. 5 is a detail view of another form of track instrument, Fig. 6 is a detail view of the train-carried tripping mechanism, Fig. 7 is a detail view in section, of the double toggle joint, and Fig. 8 is a detail of one of the shafts and its connected parts.

A indicates the rails of the main line, and B, the rails of a side track, spur or branch. 1, 1 indicate the switch points connected by the usual cross-rods 2, 2.

My invention consists in the provision of means for throwing the switch points and means for actuating such point throwing mechanism.

As one form of point throwing mechanism, I provide a four-armed spider, the alined arms 3, 3 of which lie at an angle to the alined arms 4, 4, the spider being apertured at the intersection of the arms to receive a bolt 5 carried on a stationary bed

plate 5^a, the bolt being received in a slot 6 in the bed plate, which is fastened to the road bed in any suitable manner. The slot 6 preferably lies parallel with the direction of motion of the switch tongues and the bolt is provided with a shoulder 7 received in the slot and preventing rotation of the bolt. 60

The free ends of the arms 3, 3 are pivotally connected to offset levers 8, 8', one of which is pivoted to any stationary point, as the rail A, the other lever being pivotally connected to one of the switch points 1. 65 The free ends of the arms 4, 4 of the spider are similarly connected by offset levers 9, 9', to a fixed fulcrum and to the remaining switch point 1. It will be seen that I have in effect provided a double toggle joint, consisting of the leaves 8, 3, 8', one end of which is fulcrumed and the opposite end secured to one of the switch points, together with means for guiding the joint in its movement. The ends of the levers 8, 8' are 70 turned in opposite directions, the same being true of the ends of the levers 9, 9'. 75

In order to straighten or break the toggle joints, I provide the oppositely extending rods 10, 11, the adjacent ends of the rods being preferably, though not necessarily, connected to the ends of the arms 3, 3, at their juncture with the levers 8, 8'. The opposite ends of the rods are pivotally secured to cranks 12, 12, carried by the suitably journaled shafts 13, 14, located on opposite sides of the switch points and extending preferably between the rails of the main line track. The cranks 12 and arms 3 do not extend to such a distance above the track as to be engaged by the train. 90

Track instruments are secured to the shafts and are adapted to be engaged by the train or a tripping member on the train to actuate the switch. One such track instrument adapted to be engaged by a trip on the train, is indicated in Figs. 2 and 4 and consists of an arm 15 fastened on shaft 13 at a point outside the track rail A, such arm being conveniently curved as at 16, on that side engaged by the trip to permit the trip to wipe over the arm after it has been thrown down. The hub 17 of the arm is provided with flattened faces 18 coincident with the upright and lowered positions of 100 the arm and the free end of a spring 19

bears on such faces to yieldingly retain the arm in either position to which it is thrown. A similar arm 20 is mounted on shaft 14 adjacent the inner face of one of the rails A in 5 position to be actuated by the wheel of a train passing along the rail.

As one means for tripping the arm 15 when an open switch is approached by a train, I may provide a trip consisting of a 10 bell crank lever or its equivalent 21, carried by the train. In the illustration I have shown such bell crank pivoted to a bracket 22, forming a part of the engine frame and depending a sufficient distance to support 15 the trip in position to engage the track instruments. The bracket is provided with an abutment 23 adapted to engage a stationary abutment 24 to limit backward movement of the bell crank and sustain the shock of contact of the depending arm of the bell crank and the arm 15. That face of the depending arm of the bell crank which engages the track arm is beveled off as at 25, in order to wipe over the similarly beveled face 16 of 20 the track arm when the latter is thrown down. The trip 21 is maintained yieldingly in position as shown in Figs. 2 and 6, by means of a link 27 encircled by a spring 28, the ends of which bear against a stationary 25 part of the engine and against a projection on the rod. One end of the link is connected to the trip 21, the opposite end of the link being connected to a bell crank lever 39 which is actuated by a rod 30 extending into 30 the cab of the engine. The rod 27, at its point of connection with bell crank lever 29, is slotted to permit the trip to be moved to inoperative position by engagement with the track instrument and against the tension of 35 the spring 28, when the engine is backing out of a switch, without actuating the rod 30.

The operation of so much of my invention is as follows: Assuming that the switch is 40 open as shown in Fig. 1, the track arms 15 and 20 will be in raised position, the double toggle joint 8, 3, 8' will be bent and the double toggle joint 9, 4, 9' will be straight. A train traveling in the direction of the arrow, desires to remain on the main line. 45 The trip 21, which is normally in lowered position, engages the track arm 15, throwing the latter down into substantially horizontal position. This movement of the track arm partially rotates the shaft 13 and throws its 50 arm 12 and rod 10 forward to straighten the bent toggle joint 8, 3, 8'. Since the outer end of the lever 8 cannot move longitudinally, pressure is brought to bear to swing the arm 3 on its pivot 5, such swinging 55 movement being communicated to the lever 8', tending to bring the leaves of the joint 8, 3, 8' into alinement. The pin moving in a rectilinear path defined by the slot 6,

guides the movement of the toggle joint, the straightening of which increases its length 65 and forces the switch points over to closed position. An exactly similar action will take place if the train is traveling on the main line in a direction opposite to the arrow, the wheels of the train in that case 70 engaging and actuating the track arm 20. In the event that the trip 21 or the wheel flanges become worn or do not operate to throw the track arms 15 or 20 to their full down position, the switch will nevertheless 75 be thrown over on account of the straightening action of the toggle link which will take place automatically after the knuckles 31 have passed the dead center between the fulcrum point and the point of attachment of 80 the lever 8' to the switch point 1. It is obvious that as the toggle joint 8, 3, 8', is straightened, the opposite double joint 9, 4, 9', will be bent because of the rigid connection between the arms 3 and 4. The 85 springs 19 serve as locks to releasably retain the switch in open or closed position. If a train approaching the switch in the direction of the arrow, desires to take the switch, the engineer will pull the rod 30 toward 90 himself, thereby raising the trip 21 against the tension of the spring 28 so that it cannot engage the track arm 15 to close the switch.

As one means for permitting a train on the side track to throw the switch automatically to open position to enable the train to enter the main line, I equip the shaft 14 with a fixed arm 33 lying adjacent the side track rail B, the arm 33 being arranged to extend in a direction approximately diametrically opposite the arm 20. Thus, when the arm 20 is in upright position, indicating that the switch is open, the arm 33 will extend downward somewhat below a horizontal position. Vice versa, when the arm 20 is in its depressed position extending substantially horizontally forward toward the switch, the arm 33 extends in approximate horizontal position on the opposite side of the shaft. A tongue 34 is secured to the 100 arm and extends upward through the eye 35 of a stationary bar 36 fastened in the road bed. The upper end of the tongue lies adjacent the tread of side track rail B, when the switch is closed. The wheels of a train on the side track moving out onto the main line will engage and depress the tongue to partially rotate the shaft 14 and exert a pull on the rod 11 which will bend the double toggle joint 8, 3, 8' and straighten the toggle joint 110 9, 4, 9', bringing the parts to the position shown in Fig. 1, to open the switch and permit the train to pass onto the main line. A switch stand having a quadrant plate 37 is located at the side of the track, a hinged 115 switch lever 38 being pivoted relative to the 120

quadrant and connected in any suitable manner to a link 39 which is secured to one arm of a bell-crank 40, the remaining arm being loosely pivoted to the rod 10, whereby to enable the switch to be thrown by hand. This switch lever is hinged as at 32, just outside of the quadrant to allow the end to hang down when not in use so that it will not strike any one that might be standing by 10 when a train closes or opens the switch as the case may be.

The switch lever preferably is not provided with a dog as the lever, if locked when the switch is in open position, would prevent 15 the automatic closing of the switch by a passing train, but an aperture 41 is provided in the quadrant and the lever is provided with an aperture 42 adapted to register with the aperture 41 to receive a lock of any suitable 20 description (not shown), whereby the switch may be locked in closed position, thereby rendering it impossible to use the side track without breaking the lock. The tongue 34 will be left in raised position, but 25 since it can only be operated by a train on the side track, this will do no harm when the switch is locked in closed position.

I have provided an automatic switch operating mechanism wherein the switch cannot 30 not be gigged over from one position to another, by pressure brought to bear on the switch points, owing to the fact that in either position one or the other of the double toggle joints will be straight and will prevent 35 movement of the switch except through the operation of the toggle joints themselves.

From the foregoing it is obvious that I have provided a switch which can be closed automatically by trains on the main line approaching the switch from either direction. 40 Also that the switch can be automatically opened by a train on the side track. The trip 21 on the engine is normally in operative position to engage the track arm.

45 When the engineer wishes to take the side track, he will raise the trip by pulling back on the rod 30, until the trip 21 passes over the track arm 15 and then will merely release his hold on rod 30, whereupon it will 50 automatically move to its normal position by the energy of spring 28, which is compressed when rod 30 is pulled back by the engineer. The trip is hinged so that when a train is backing out of the switch, the trip will ride

55 over the track arm without bringing pressure to bear thereon and without operating the rod 30, as link 27 is loosely connected to the bell crank 29 to permit the link to rise without moving the bell crank 29. When a train 60 passes head on out of the switch onto the main line, or backs in on the switch, the engineer need pay no attention as the trip will lie on the opposite side of the track from the

track arms and hence, they do not come in contact with each other. Turn buckles may 65 also be provided on the rods 10, 11 and 39, for purposes of adjustment.

Changes might be made in the form and arrangement of the several parts described, without departing from the spirit and scope 70 of my invention.

Having thus fully disclosed my invention, what I claim as new, is:—

1. An automatic switch mechanism comprising movable switch points, means for 75 shifting the switch points laterally, a car device, means for retaining the car device normally in operative position, means projecting into the path of movement of the car device on the main line when the switch 80 is open and actuated thereby for automatically operating the switch shifting mechanism to throw the switch to closed position, and means on the side track automatically operated by the wheels of an out passing 85 train for throwing the switch to open position.

2. An automatic switch mechanism for railways, comprising switch points, suitably journaled shafts located on opposite sides of 90 the switch, train-actuated track arms carried by the shafts and adapted to be raised when the switch is in open position, a car device normally in position to automatically actuate the track arms when raised, switch 95 shifting means connected to the switch points, means connecting the shafts and the switch-shifting means, and yieldable locking means engaging the shafts for preventing accidental movement thereof and retaining 100 them in their adjusted positions.

3. An automatic switch mechanism for railways comprising laterally movable switch points, means connected with the switch points for shifting them laterally, suitably 105 journaled shafts located on opposite sides of the switch, train-actuated track arms carried by the shafts to permit the switch to be automatically closed by trains traveling in either direction on the main line, means connecting the shafts and switch shifting means, members fast on the shafts and having two flattened faces corresponding to the positions of the track arms when at one or the other of their limits of movement, and 110 springs engaging the flattened faces.

4. An automatic switch mechanism for railways comprising movable switch points, means connected with the switch points for shifting them, suitably journaled shafts located on opposite sides of the switch, train-actuated track arms carried by the shafts to permit the switch to be automatically closed by trains traveling in either direction on the main line, a bell crank separate from the 115 120 automatic switch-operating means, one arm

- of the bell crank being connected by a pin and slot to one of the rods, a pivoted switch lever, and means connecting the bell crank and switch lever.
5. An automatic switch mechanism for railways, comprising laterally movable switch points, means for shifting the switch points, a track arm, means connecting the track arm and switch shifting mechanism, a trip hinged to the locomotive, an abutment against which the trip normally rests to limit movement of the trip in one direction, yielding means for automatically retaining the trip in operative position, and means for actuating the trip to move it to inoperative position against the tendency of the means for normally maintaining the trip in operative position.
6. An automatic switch mechanism for railways comprising laterally movable switch points, a main line, a side track, means connected with the switch points for shifting them laterally, and means on the side track adapted to be automatically engaged by a train and connected to the switch shifting means for opening the switch to a train leaving the side track.
7. An automatic switch mechanism for railways comprising laterally movable switch points, a main line, a side track, means connected with the switch points for shifting them laterally, a suitably journaled shaft, a projecting arm fast on the shaft, a wheel-actuated tongue pivoted to the arm, a guide for the tongue, and means connecting the shaft and switch shifting mechanism.
8. A switch mechanism for railways comprising a laterally movable switch, a double toggle joint consisting of levers and a semi-rotatable arm connecting the adjacent ends of the levers, one end of the toggle joint being stationarily fulcrumed, the opposite end being secured to the switch, and means for actuating the toggle joint to shift the switch.
45. 9. A switch mechanism for railways comprising a laterally movable switch, a double toggle joint having at least two knuckles, one end being stationarily fulcrumed, the opposite end secured to the switch, the ends of the joint being offset relative to the knuckles when the joint is straight, and means for actuating the joint to operate the switch.
50. 10. A switch mechanism for railways comprising a laterally movable switch, a double toggle joint, one end of which is stationarily fulcrumed, the opposite end being secured to the switch, a movable bolt to which the joint is pivotally secured, means engaged by the bolt for causing it to travel in a rectilinear path, and means for actuating the toggle joint to shift the switch.
55. 11. A switch mechanism for railways comprising a laterally movable switch, a double toggle joint consisting of a pair of levers, the outer end of one lever being stationarily fulcrumed, the outer end of the opposite lever being secured to the switch, and a link pivotally connecting the adjacent ends of the levers, a movable bolt on which the link is pivotally mounted, means for guiding the bolt, and means for actuating the toggle joint to shift the switch.
12. A switch mechanism for railways comprising a laterally movable switch, a double toggle joint comprising a pair of levers, and a link pivotally connecting the inner ends of the levers, the outer end of one lever being stationarily fulcrumed, the outer end of the remaining lever being secured to the switch, the outer ends of the levers being laterally offset in opposite directions, and means for actuating the joint to shift the switch.
13. A switch mechanism for railways comprising a laterally movable switch, a pair of double toggle joints, one end of each joint being stationarily fulcrumed, the remaining ends of the joints being secured to opposite switch points, and means for actuating the toggle joints.
14. A switch mechanism for railways comprising a laterally movable switch, a pair of double toggle joints, one end of each joint being stationarily fulcrumed, the remaining ends of the joints being secured to opposite switch points, the double toggle joints being interconnected, and means for actuating one of the toggle joints to shift the switch.
15. A switch mechanism for railways comprising a laterally movable switch, a spider having divergent arms, levers connected to the arms of the spider to form a pair of double toggle joints, the outer ends of certain of the levers being stationarily fulcrumed, the outer ends of the remaining levers being secured to the switch, a bolt on which the spider is pivoted, means for controlling the direction of movement of the bolt, and means for actuating at least one of the double toggle joints.
16. A switch mechanism for railways comprising a laterally movable switch, a double toggle joint, one end of which is stationarily fulcrumed, the opposite end being secured to the switch, a laterally movable pivot located intermediate the ends of the joint, and means for actuating the joint.
17. A switch mechanism for railways comprising a laterally movable switch, a double toggle joint, one end of which is stationarily fulcrumed, the opposite end being secured to the switch, a laterally movable pivot located intermediate the ends of the joint, a rod connected with the joint, and a train-actuated means for throwing the rod to actuate the joint.

18. A switch mechanism for railways, comprising a laterally movable switch, a car device normally retained in operative position, track devices on the main track on opposite sides of the switch, means connecting the switch and track devices, the devices each adapted to project into the path of movement of the car device when the switch is open, and a trip on the side track connected 10 with one of the track devices and adapted to

be automatically engaged by an out-passing train on the side track, only when the switch is closed, to open the switch.

In testimony whereof, I affix my signature in presence of two witnesses.
